UNITED STATES PATENT OFFICE.

PETER IRVING WOLD, OF EAST ORANGE, NEW JERSEY, ASSIGNOR TO WESTERN ELECTRIC COMPANY, INCORPORATED, OF NEW YORK, N. Y., A CORPORATION OF NEW YORK.

HIGH-FREQUENCY MODULATION DEVICE

Application filed May 28, 1918. Serial No. 237,120.

To all whom it may concern:

Be it known that I, PETER IRVING WOLD, a citizen of the United States, residing at East Orange, in the county of Essex, State of New Jersey, have invented certain new and useful Improvements in High-Frequency Modulation Devices, of which the following is a full, clear, concise, and exact description.

The object of this invention is to provide a means and method for producing modulated high frequency oscillations.

This invention relates to a system wherein a condenser transmitter is associated with an electronic or other potential operated device for modulating or otherwise varying oscillations in accordance with variable wave signals.

In one aspect the invention resides in associating a condenser having an electrode adapted to vibrate at the frequency of sound waves with a thermionic or equivalent repeating device having a feed-back connection.

One object is to so associate a condenser transmitter with a high frequency generator that the condenser may be polarized to a sufficiently high degree for efficient action without disturbing the action of the generator.

The invention as herein exemplified, resides in a system in which a condenser transmitter is associated with a typical form of oscillation generator of the audion or equivalent electronic discharge type for modulating the oscillations generated thereby in accordance with speech or other signals.

Condenser transmitters have heretofore been of slight value for practical application because, while they are quite free from distortion, the systems in which they were employed were of small efficiency from an energy standpoint. However, with the development of voltage operated modulating devices of the type herein disclosed which require practically no current but only a change of potential to secure effective modulation, the utilization of condenser transmitters for practical operation in modulating systems becomes possible. This invention has for a primary object the provision of means for accomplishing this purpose. This highly desirable result is further assisted by the development and utilization of substan-

tially distortionless and very efficient amplifying devices whereby modulated oscillations of small energy may be amplified once or successively before utilization. The use of such amplifiers is, however, well known in the art and constitutes no part of the present invention which broadly relates to means for associating a device of the thermionic discharge type with a condenser telephone as a means for varying repeated or generated oscillations.

For the purpose of explaining the application and scope of the invention, reference is made to the accompanying drawings wherein one arrangement of circuits and devices for carrying out the invention is diagrammatically shown.

The highly evacuated tube 1 of the audion type contains anode 2, cathode 3 and impedance varying element or grid 4. A tuned circuit including variable capacity 5 and inductance 6 is connected between the anode and cathode. The frequency of oscillations generated may be conveniently varied by changing the tuning of this circuit. Condenser transmitter 7 is conventionally shown as connected between the grid 4 and cathode 3. One terminal of the condenser is conductively connected to the grid and the other to the cathode. High resistance 8 is in parallel with transmitter 7. The resistance 8 allows the condenser transmitter 7 to be polarized and its value is large to prevent short-circuiting of speech frequency variations induced by the condenser transmitter 7. Battery 9 serves to polarize the transmitter 7, battery 10 serves to apply a suitable, preferably negative potential to the grid 4 and battery 11 provides space current between the anode and cathode. A feed-back connection 12 includes coil 13 which is coupled to coil 6 for feeding back energy to the input circuit, which is connected between electrodes 3 and 4 of the tube, to cause oscillations. Capacity 14 is preferably variable and is adjusted so that high frequency variations will pass readily but considerable impedance will be offered to low frequency variations, thereby preventing variations of potential upon the grid, caused by condenser transmitter 7, from being short-circuited. Inductance 15 on the other hand is adjusted to allow low frequency variations to pass readily but to prevent high frequency varia-

tions which are fed back through connection 12 from being short-circuited through transmitter 7. Coil 16 is coupled to coil 6. Variable potentials upon the grid of the modulating tube will cause corresponding variation of amplitude of the generated oscillations which will then be modulated in accordance with signals. Line 17 and coil 16 typify any suitable means for leading away the modulated high frequency currents for wire or wireless signaling or any other desired purpose.

It should be noted that this system possesses the advantage that no current is normally flowing in the low frequency circuit associated with the input of the modulator as in the case when a microphone circuit containing a battery is employed. Instead, in accordance with this invention there is normally maintained a system of balanced forces comprising the electromotive force of the battery 9 and the static charges upon the plates of condenser transmitter 7. When the transmitter operates, an unbalanced condition is effected which causes an additional electromotive force corresponding to the signal to be impressed upon the grid of the modulator.

The invention is not limited to the embodiment herein described and illustrated but may be involved in other constructions. The appended claims define the novel features of the invention both broadly and specifically.

35. What is claimed is:

1. The combination of an oscillation generating system including an input circuit, an output circuit and a feed-back circuit, and a condenser transmitter conductively connected to the input circuit thereof for modulating in accordance with speech the oscillations produced by said generating system.

2. The combination of an oscillation generator including an input circuit, an output circuit and a feed-back circuit, and a condenser transmitter operatively associated with one of said circuits for modulating in accordance with speech the oscillations produced thereby.

3. In combination, an oscillation generating system including spaced electrodes between which a space discharge occurs and an impedance varying element for varying the impedance of said space, and a condenser transmitter for changing the potential of said impedance varying element in accordance with speech waves.

4. In combination, a generator adapted to produce continuous electrical oscillations of constant amplitude, and a condenser transmitter operatively associated with said generator for varying the oscillations in accordance with speech waves.

5. A generator of oscillatory electric cur-

rents including an evacuated vessel containing a cathode and an anode, an impedance varying element therefor, a source of energy, and circuit connections in combination with a condenser transmitter conductively connected to said circuit connections to vary the oscillations generated in accordance with speech waves.

6. In combination, an evacuated vessel containing an anode and a cathode, an impedance varying element for controlling the current between said anode and said cathode, a tuned circuit connected between said anode and said cathode, an input circuit between said cathode and said impedance varying element, a condenser transmitter adapted to be operated by speech waves included in said input circuit, and a feed-back connection from said tuned circuit to said input circuit.

7. The combination of an electronic discharge device having an input circuit, an output circuit, and a feed-back connection with a condenser transmitter adapted to be actuated by speech waves operatively associated with one of said circuits, and a potential source for polarizing said transmitter.

8. The combination of an electronic discharge device having an input circuit, an output circuit and a feed-back connection, a condenser transmitter adapted to be actuated by speech waves included in said input circuit, and means for polarizing said transmitter.

9. The combination of an electric discharge device with means comprising a cathode, an anode and an impedance control electrode for producing electrical oscillations and a condenser transmitter adapted to be actuated by speech waves for causing the discharge device to vary said oscillations repeated thereby in accordance with speech waves acting upon said condenser transmitter.

10. The combination of an electronic discharge repeater with a source of high frequency variations connected to the input circuit thereof, a condenser transmitter adapted to be actuated by speech waves, and connecting means for causing said repeater to repeat the high frequency variations in a varying manner dependent on varying conditions of said condenser.

11. The combination of an electronic discharge amplifier with a source of high frequency variations connected to the input circuit thereof, a condenser transmitter adapted to be operated by speech waves, and connecting means for causing said amplifier to variably amplify the high frequency variations in accordance with instantaneous changes of capacity of said transmitter.

12. In combination, means for establish-

- ing an electron stream, means for maintaining a static charge in the vicinity of said stream to act thereupon, means for periodically varying said charge at high frequency, 5 means to normally produce a static balancing of a plurality of electromotive forces, means for disturbing the balance in accordance with speech waves, and means for causing the unbalanced condition to maintain 10 a slowly varying additional charge in the vicinity of said stream.
13. A high frequency generating system comprising an evacuated vessel, an anode and a cathode therefor, means for producing current between said anode and cathode, impedance controlling means for varying the current therebetween, an input and an output circuit for said vessel, said circuits being coupled, a condenser transmitter serially arranged between said cathode and impedance controlling means, a tuned circuit for determining the frequency of the generated current substantially independently of the capacity of the condenser transmitter, and means for preventing said transmitter from shunting high frequency current from said input circuit. 15
14. The method which comprises establishing an electron stream, maintaining a static charge in the vicinity of said stream to act thereupon, periodically varying said static charge at high frequency, normally producing a static balancing of electromotive forces, disturbing the balance thereof in accordance with speech waves, and causing the unbalance to maintain a slowly 20
- varying additional charge in the vicinity of said stream.
15. The method which comprises establishing an electron stream, maintaining a static charge in the vicinity of said stream to act thereupon, periodically varying said static charge at a high frequency, normally maintaining a system of balanced electromotive forces comprising static charges, 25 periodically varying the spacial relation of said charges at a relatively low frequency to unbalance the system, and causing said unbalance to maintain a correspondingly varying additional charge in the vicinity of 30 said stream to vary the same.
16. In combination, an electron discharge device having an anode, a cathode, and an element for controlling the impedance therebetween, a source of energy for supplying current between the cathode and the anode, circuit arrangements connected to said anode, cathode, and element and forming with said electron discharge device means for generating oscillations of a given frequency whose amplitude is dependent upon the average potential of said impedance controlling element, and a condenser transmitter having a source of potential associated therewith connected to said device for varying the potential of said element with respect to said cathode in accordance with speech waves. 35
- In witness whereof, I hereunto subscribe my name this 21st day of May, A. D. 1918.
- PETER IRVING WOLD.
